UNITED STATES PATENT OFFICE.

WILLIAM M. GERKEY, OF CARTHAGE, MISSOURI, ASSIGNOR OF ONE-HALF
TO JOHN LEWIS GERKEY, OF SAME PLACE.

BUTTON-SETTING MACHINE.

SPECIFICATION forming part of Letters Patent No. 428,903, dated May 27, 1890.

Application filed May 20, 1889. Serial No. 311,386. (No model.)

To all whom it may concern:

Be it known that I, WILLIAM M. GERKEY, a citizen of the United States, and a resident of Carthage, in the county of Jasper and State 5 of Missouri, have invented certain new and useful Improvements in Shoe-Button-Fastening Machines; and I do hereby declare that the following is a full, clear, and exact description of the invention, which will enable 10 others skilled in the art to which it appertains to make and use the same.

This invention relates to shoe-button-fastening machines.

The object is to produce a machine which 15 shall be continuous in operation—that is, one which will clinch a button at one point and at the same time thread another button and drop it in position to be clinched.

With these objects in view the invention 20 consists in the improved construction and combination of parts of a shoe-button-fastening machine, as will be hereinafter fully described in the specification, illustrated in the drawings, and pointed out in the claims.

25 In the accompanying drawings, forming part of this specification, in which like letters of reference indicate corresponding parts, I have illustrated one form of device embodying the essential features of my invention, 30 although the same may be carried into effect in other ways without in the least departing from the spirit thereof, and in these drawings—

Figure 1 is a perspective view of my improved shoe-button-fastening machine. Fig. 35 2 is a front elevation of the same. Fig. 3 is a similar view with a portion removed, showing more particularly the knife for cutting the wire used to form the staples, and also 40 the die for clinching the staples. Fig. 4 is a side elevation, partly broken away, showing the mechanism for operating the die or former on which the staples are pressed into shape. Fig. 5 is a rear elevation. Fig. 6 is a detail 45 view of the front plate of the machine, taken from the rear side. Fig. 7 is a detail view of the combined knife and die. Fig. 8 is a detail view of one of the clamping-jaws. Fig. 9 is a detail view of the movable jaw for hold-

ing the crimper in place, showing an opening 50 therein through which the wire for forming the staples is inserted. Fig. 10 is a detail view of one of the button-tubes, showing its peculiar construction; and Fig. 11 is a detail view of an arm for preventing the buttons 55 dropping to the clinching mechanism faster than desired. Fig. 12 is a front view showing the wire engaged by the jaws, the dotted lines indicating the same as passing through the eye of the button.

Referring to the drawings, A designates the frame or standard of the machine to which the working parts are secured, and which consists of an upright 1 and an arm 2 extending at right angles to the same. To the outer 65 end of this arm is secured or may be formed integral therewith a vertical piece 3, provided with a recess 4, which forms a guide for the combined knife and die 5, which, when the machine is in operation, performs the triple 70 function of forming the wire into a staple, cutting the wire and then crimping or clinching the staple thus formed in place upon the shoe or other article.

As I will have occasion to refer frequently 75 to the knife and die, I will, for the sake of brevity, designate it throughout the specification as the "crimper." The crimper is operated by means of a lever 6, having one end formed into a yoke 7, which is pivoted to upwardly-extending shoulders 8 on a standard 9, said standard being provided with the downwardly-extending portion, which fits the rear side of the vertical piece 3, and is secured thereto by means of screw-bolts or equivalents, the opposite end of the lever pivoted to 80 a rod 10, which passes down to the bottom of the frame, at which point a spring-actuated foot-lever 11 is pivoted. The knife 12, which forms the top portion of the crimper, is provided with a recess 13, terminating at the top with a compound slot 14, in which the shank of the button rests, while one side is provided with a beveled cutting-edge 15, as seen clearly 85 in Fig. 7. As now seen, the knife can only 90 be used on one side; but, if desired, it may be provided with a cutting-edge on both sides, thereby making it interchangeable, so that 95

when one jaw becomes dulled from use the knife may be turned around, and thus present a fresh cutting-edge.

The crimper is provided with a vertical slot 16, through which works a die 17 for forming the staple, said die being provided with an upper rounded tongue or lip, as shown in Fig. 3, upon which the button-shank rests vertically, so as to present the eye on a vertical plane.

10 This die is caused to reciprocate by means of a lever 18, said lever extending through an elongated slot in the arm 2, the upper end thereof being pivoted within the bifurcated end of an arm 18'. This lever is actuated by 15 a pivoted arm 19, the lower end of said arm journaled in the bifurcated end of an angular bracket 19', while its upper end is bifurcated and adapted to receive the lower end of said lever 18. Through the slot 16 in the lower 20 end of the crimper, and through the registering slot 4 in the vertical piece 3, extends the shank of a bracket or bearing 21, which bears against the rear of the vertical piece 3, and is adapted to move vertically when movement 25 is imparted to the crimper. The bracket or bearing has journaled therein a roller 20, which engages the forward end of a weighted pawl 22 when the crimper is moved up, forces the lever out, and thus draws the die back; 30 but when the crimper descends the pawl is tripped, and thus allows the lever to remain stationary.

In order to cause the die to resume its normal position, a coiled spring 23 is mounted 35 behind it, which, when pressure is removed from the lever 18, causes the die to be forced out in the position shown in Fig. 3. The object of having the die reciprocate will be fully described farther on.

40 At the upper end and at one side of the crimper is secured a slotted cam 24, which operates the mechanism for feeding buttons to the die. This mechanism consists of a pivoted lever 25, which is bifurcated at its upper end, the said bifurcated portion having journaled therein a roller 26, working in the slot in the cam. At a point about midway of the length of this lever and secured to the side of the vertical piece 3 is a laterally-extending arm 27, upon which is mounted a 45 slide 28, carrying a pivoted jaw 29 and a jaw 30 below it. These jaws, as will be observed, are serrated at their meeting edges, so as to clamp the wire firmly in place. The lower 50 end of the jaw 29 is provided with a pin 31, which engages a slot 32, by means of which the jaw will be opened when the lever 25 is moved out from the vertical piece and closed when moving in. This will be readily understood by referring to the drawings, for when the lever is raised the roller will enter the slanting portion of the slot in the cam and thus draw the lever out and thereby open the jaw; but when the lever is brought down 55 the jaw will be closed and firmly clamped as soon as the roller enters the vertical part of the slot.

The wire for forming the staples is fed from a spool 33, which is mounted upon a bracket 34 and passes between a series of 70 rollers 35 previous to passing between the jaws of the clamps. The object of this construction is to have the wire taut at all times, so as to prevent any buckling or bending, which would tend to interfere with the perfect working of the device.

The button-feeding mechanism consists of a reel B, which is mounted upon a shaft or rod 36, secured to a brace or bracket 37 upon the top of the frame A. This reel consists of 80 a series of tubes 38, which are formed in cross-section to conform to the shape of the button. This reel is revoluble and is brought over a feed-chute 39, down which the buttons pass to be threaded previous to being secured 85 upon the shoe. The feed-chute consists of two portions—an outer portion 40, constructed, preferably, of a flat piece of metal, and the inner portion 41, constructed of two pieces of metal, so as to form a slot 42, through which the 90 shank of the button extends—said chute being connected at its upper end by means of a sleeve 40'. In order to prevent the buttons falling faster than desired, a rod 43 is pivoted upon the face-plate, and is provided with two crescent-shaped pieces of metal 44, one of which works in the slot of the feed-chute and the other through a slot 45, the latter crescent-shaped piece being engaged by a pin 46 upon the knife, 95 said pin extending forwardly through the slot 100 45. This is desirable, inasmuch as there should be some check to the fall of the button, which is accomplished by the shank of a button passing into the concavity of the crescent-shaped piece of metal, which works in the slot of the 105 feed-chute and is there held until the crimper is moved upward and the pin 46 engages the other crescent-shaped piece, the concavity of 110 that piece facing inward. The moment the pin strikes the end of this latter crescent-shaped piece the central crescent is turned, thus releasing the button and permitting the shank of the same to fall upon the curved lip of the die. This provides for the buttons falling at regular intervals—that is to say, 115 after the wire has been passed through the eye of the button, in the manner hereinafter explained, and the wire bent into proper shape the crimper is moved upward, the button upon the die is then released, and, as 120 above stated, as soon as the pin 46 trips its appropriate crescent, the button and knife descend together. The chute is further provided with set-screws 47, by means of which the chute may be adjusted to fit different-sized buttons. Immediately below the chute 125 is pivoted an arm 48, which is designed to prevent the buttons dropping after they have escaped from the crescent-shaped pieces—that is to say, this arm is designed to press against 130 the head of the button when the same rests upon the die and holds it in proper position during the operation of passing the wire through the eye of the same, and to cease

pressure after the wire has been passed through the eye and cut by the action of the knife. In other words, when the crimper is descending and the slide moving inward in order to thread the eye of the button the arm 48 is exerting a pressure upon the button-head so as to hold it in position, as it will be noticed that the outer end of this arm is inclined and adapted to be engaged by the forwardly-extending pin 27' on the inward stroke of the slide. After the threading and cutting have been completed there is no longer any necessity for retaining the button upon the die, and as the crimper is moved upward the slide 10 of course is moved outward and the pressure of the pin 27' upon the end of the lever is released. This arm is held out of contact with the feed-chute by means of a spring 49; but when, as above explained, the slide is forced 20 inwardly and the forwardly-extending arm thereof acts upon the pivoted arm 48 the pressure of this spring 49 is overcome. The die 50, upon which the staple is clinched, is mounted within the outer end of an arm 51, pivoted to 25 shoulder 52, formed near the lower portion of the upright 1. This arm extends through a slot 53 formed within the said upright and is engaged by a lever 54, carrying a cam 55. Pivoted to the lever 6 is a rod 10, in which is 30 formed a slot 57, through which the arm 54 works. This rod extends down to and is pivoted to the foot-lever at the base of the machine. Within the slot before referred to is mounted a curved spring 58, which bears upon 35 the arm 54 to cause it to resume its normal position after having been raised by the lever 6. It is to be understood that the foot-lever just referred to operates the extra device—that is, feeds the wire to the button and operates the knife to cut the wire, moves the die back to allow the button to drop to the clincher, and clinches the staple in place upon the shoe or other article. In order to 40 understand how this is brought about, I will now proceed to describe the manner in which the device is operated.

The device being in the position shown in Fig. 1, the foot-lever is pressed and draws the lever 6 down, which movement partially rotates the rod carrying the crescent-shaped stops and releases one button, which drops upon the die 17. As the lever 6 is thus drawn down, the slide 28 is moved inwardly through the medium of the pivoted lever 25, 50 working in the slotted cam 24, and at the same time the grip of the jaws upon the wire is released by action of the pin 31 from the lower end of the pivoted jaw 29, engaging the slot 32 in the lever 25. The wire thus being 55 released and the slide moving inwardly, said wire is necessarily forced laterally and passed through the eye of the button. After the crimper has reached its extreme downward limit, the shape of the compound slot in the upper portion thereof has the effect of bending the wire and the inclined cutting-edges

of the knife of cutting the same. It will be observed, however, that the highest point of the compound slot extends sufficiently upward to prevent the upper end thereof from 70 coming in violent contact with the upright edge of the eye of the button, thus preventing damage thereto. After pressure upon the treadle is stopped, of course the lever 6 moves upward by the recoil of the spring 59, and at 75 the same time the die 17 is moved inwardly, while the slide moves outwardly. In this manner the support for the button is removed, and the pressure upon the spring 48 being no longer exerted, the button and staple formed 80 in the eye thereof fall upon the die 50, and when the foot-lever is again pressed down the staple thus formed will be securely clinched in place. As the lever 6 is raised each time, the arm carrying the die 50 is forced down 85 by means of the spring before referred to, and thus allows the article to be withdrawn from under the die. As each button drops to its position, it is held in place by means of two springs 60, so that as the die 50 leaves 90 the bottom of the vertical piece 3 the buttons will be prevented from dropping from the machine.

It will be observed that the side of the guide through which the wire passes is inclined, as shown at 61, and is provided with an opening 62, through which the wire passes to hold it steady. The object of having it in this way is that the wire will be cut on an angle instead of straight, thereby presenting 95 a sharp point, so that the puncturing of the leather or other material will be facilitated.

It will thus be seen from the foregoing description that although this device is comparatively simple of construction it will be 105 found of the highest efficiency and durability in use, and may be constructed at but a slight expense, and will greatly reduce the cost and trouble of securing the buttons in place upon shoes.

Having thus fully described my invention, what I claim as new, and desire to secure by Letters Patent, is—

1. In a button-setting machine, the combination of an upright or standard having an 115 arm extending at right angles thereto, the latter formed or provided with a vertically-extending piece, a standard having its rear end flanged downwardly and secured to the vertical piece and its forward end extending 120 upwardly and bifurcated, a lever having its end formed into a yoke which is journaled to the bifurcated portion of the standard, a vertical arm connecting the rear end of the lever, said arm being provided near its lower end 125 with an elongated slot, a lever journaled in suitable bearings in the lower end of the frame of the device and having its rear end passing into the slot of the same, carrying on its forward end a clinching-die, a lever formed 130 or provided on its forward end with a cam, said cam working in the slot of the frame and

- bearing upon the end of the die-carrying lever, the rear end of said cam-lever passing into the elongated slot of the vertical arm, a spring connected to said vertical arm and bearing upon the end of the cam-lever, and a spring-actuated treadle pivoted in a suitable frame and connected to the vertical arm, substantially as set forth.
2. In a button-setting machine, the combination of a standard formed or provided with an extension at right angles thereto, said extension having an elongated horizontal slot therein intersected centrally by a vertical slot, a bracket secured to the vertical piece near the lower end thereof and upon the rear side, a lever pivoted to said bracket, a weighted pawl pivoted in said lever, a spring-actuated staple-forming die passing into the elongated slot of the right-angled extension, a vertical arm having its upper end pivoted to a suitable bracket and passing through the vertical intersecting slot of the right-angled extension, its lower end passing into the bifurcated end of the rearwardly-extending portion of the lower vertical arm or lever, a vertically-reciprocating crimper and knife provided near its lower end with an elongated slot through which the die works, and a bracket having the shank thereof extending through the slot of the vertical piece and secured to the lower end of the combined crimper and knife, said bracket having a suitable roller journaled therein, substantially as set forth.
3. In a button-setting machine, the combination of a standard or frame, a vertical approximately U-shaped bracket secured thereto, said bracket provided with an upwardly-extending arm, a revolute reel consisting of annular top and bottom pieces connected by a series of button-tubes conforming to the shape of the button, and a feed-chute for conveying the buttons from said tubes, said chute consisting of two sections, the forward section being composed of one piece and the rear section of two pieces, with an intervening space between, said several pieces being arranged obliquely and curved slightly inwardly, substantially as set forth.
4. In a button-setting machine, the combination of a standard or frame, a vertical bracket, approximately U-shaped, secured thereto, said bracket provided with an upwardly-extending arm, a revolute reel consisting of annular top and bottom pieces connected by a series of button-tubes conforming to the shape of the button, a feed-chute for conveying the buttons from said tubes, said chute consisting of two sections, the forward section consisting of one piece and the rear section of two pieces, with an intervening space between, a sleeve for connecting the upper ends of the sections of the chute, and set-screws to adapt the chute to different sizes of buttons, substantially as set forth.
5. In a button-setting machine, the combination of a standard formed or provided with an extension at right angles thereto, a vertical piece secured to said extension, a vertically-reciprocating combined knife and crimper working in suitable ways upon said vertical piece and provided with a forwardly-extending pin, a spring actuated alternately inward and outward moving staple-forming die, a front plate provided with an elongated slot, a transverse spring-actuated shaft mounted in the upper end of said plate, said shaft carrying central and end crescent-shaped stops, the end stop constructed to be operated by the forwardly-extending pin of the combined knife and crimper working through a side slot in the front plate and tripping said stop, so that the button engaged by the central stop may pass to the die, substantially as set forth.
6. In a button-setting machine, the combination of a standard formed or provided with an extension at right angles thereto, a vertical piece secured to said standard, a vertically-reciprocating combined knife and crimper working in suitable ways upon said vertical piece, a spring-actuated and alternately forwardly and rearwardly moving staple-forming die, a front plate provided with a central longitudinal slot for the reception of the shank of the button, and springs having their upper ends secured to opposite sides of the front plate and having their lower free ends bearing against the lower end of the longitudinal slot, in combination with a horizontally-pivoted clinching-die acting against the lower end of the combined knife and crimper, a chute provided on its inner side with a longitudinal slot, the lower end thereof registering and communicating with the upper end of the longitudinal slot of the front plate, a spring bearing against the lower end of the chute, and means for regulating the tension of said spring, substantially as set forth.
7. In a button-setting machine, the combination of a standard formed or provided with an extension at right angles thereto, a vertical piece secured to said standard, a combined knife and crimper, a lever for operating said knife and crimper, a cam having a laterally-extending arm connected to the operating-lever, a lever pivoted to the side of the vertical piece, said lever having its upper end bifurcated and having journaled in said bifurcated portion a suitable roller, the latter working in the irregular slot of the cam, an arm extending laterally from the front vertical piece, and a wire-carrying slide mounted upon said arm and connected to the lever pivoted to the side of the vertical piece, whereby when the operating-lever is moved downwardly the slide will be moved inwardly, and when the operating-lever is moved upwardly the slide will be moved outwardly, substantially as set forth.
8. In a button-setting machine, the combination of a standard formed or provided with an extension at right angles thereto, a vertical piece secured to said extension, a vertically-reciprocating combined knife and crimper working in suitable ways upon said vertical piece and provided with a forwardly-extending pin, a spring actuated alternately inward and outward moving staple-forming die, a front plate provided with an elongated slot, a transverse spring-actuated shaft mounted in the upper end of said plate, said shaft carrying central and end crescent-shaped stops, the end stop constructed to be operated by the forwardly-extending pin of the combined knife and crimper working through a side slot in the front plate and tripping said stop, so that the button engaged by the central stop may pass to the die, substantially as set forth.

nation of a standard formed or provided with an extension at right angles thereto, a vertical piece secured to said extension, a vertically-reciprocating combined knife and crimper working in suitable ways upon said vertical piece and provided with a forwardly-extending pin, a spring actuated alternately inward and outward moving staple-forming die, a front plate provided with an elongated slot, a transverse spring-actuated shaft mounted in the upper end of said plate, said shaft carrying central and end crescent-shaped stops, the end stop constructed to be operated by the forwardly-extending pin of the combined knife and crimper working through a side slot in the front plate and tripping said stop, so that the button engaged by the central stop may pass to the die, substantially as set forth.

6. In a button-setting machine, the combination of a standard formed or provided with an extension at right angles thereto, a vertical piece secured to said standard, a vertically-reciprocating combined knife and crimper working in suitable ways upon said vertical piece, a spring-actuated and alternately forwardly and rearwardly moving staple-forming die, a front plate provided with a central longitudinal slot for the reception of the shank of the button, and springs having their upper ends secured to opposite sides of the front plate and having their lower free ends bearing against the lower end of the longitudinal slot, in combination with a horizontally-pivoted clinching-die acting against the lower end of the combined knife and crimper, a chute provided on its inner side with a longitudinal slot, the lower end thereof registering and communicating with the upper end of the longitudinal slot of the front plate, a spring bearing against the lower end of the chute, and means for regulating the tension of said spring, substantially as set forth.

7. In a button-setting machine, the combination of a standard formed or provided with an extension at right angles thereto, a vertical piece secured to said standard, a combined knife and crimper, a lever for operating said knife and crimper, a cam having a laterally-extending arm connected to the operating-lever, a lever pivoted to the side of the vertical piece, said lever having its upper end bifurcated and having journaled in said bifurcated portion a suitable roller, the latter working in the irregular slot of the cam, an arm extending laterally from the front vertical piece, and a wire-carrying slide mounted upon said arm and connected to the lever pivoted to the side of the vertical piece, whereby when the operating-lever is moved downwardly the slide will be moved inwardly, and when the operating-lever is moved upwardly the slide will be moved outwardly, substantially as set forth.

8. In a button-setting machine, the combination of a standard formed or provided with an extension at right angles thereto, a vertical piece secured to said extension, a vertically-reciprocating combined knife and crimper working in suitable ways upon said vertical piece and provided with a forwardly-extending pin, a spring actuated alternately inward and outward moving staple-forming die, a front plate provided with an elongated slot, a transverse spring-actuated shaft mounted in the upper end of said plate, said shaft carrying central and end crescent-shaped stops, the end stop constructed to be operated by the forwardly-extending pin of the combined knife and crimper working through a side slot in the front plate and tripping said stop, so that the button engaged by the central stop may pass to the die, substantially as set forth.

nation of a standard formed or provided with an extension at right angles thereto, a vertical piece secured to said standard, a combined knife and crimper, a lever for operating said knife and crimper, a cam having a laterally-extending arm connected to the operating-lever, a lever pivoted to the side of the vertical piece, said lever having its upper end bifurcated and having journaled in said portion a suitable roller, the latter working in the irregular slot of the cam, an arm extending laterally from the front vertical piece, and a wire-carrying slide mounted upon the said arm, having a lower rigid jaw and an upper pivoted jaw secured thereto, said upper jaw extending downwardly and provided with a rearwardly-extending pin constructed to pass into the elongated slot in the lever pivoted to the said vertical piece, substantially as set forth.

9. In a button-setting machine, the combination of a standard formed or provided with an extension at right angles thereto, a vertical piece secured to said standard, a combined knife and crimper, a lever for operating said knife and crimper, a cam having a laterally-extending arm connected to the operating-lever, a lever pivoted to the side of the vertical piece, said lever having its upper end bifurcated and having journaled in said bifurcated portion a suitable roller, the latter working in the irregular slot of the cam, an arm extending laterally from the front vertical piece, a wire-carrying laterally-reciprocating slide mounted upon said arm and connected to the lever pivoted to the side of the vertical piece, a series of rollers mounted upon the extreme outer end of said laterally-extending arm, and a bracket having mounted thereon a spool, substantially as set forth.

10. In a button-setting machine, the combination of a standard formed or provided with an extension at right angles thereto, a vertical piece secured to said standard, a combined knife and crimper, said knife having its cutting-edge inclined, a cutting-piece fitting against the edge of said knife and having an inclined cutting-edge registering with the inclined edge of the knife proper, and also provided with a transverse wire-guiding perforation registering with a similar perforation in the knife, a lever for operating said knife and crimper, a cam having a laterally-extending arm connected to the operating-lever, a lever pivoted to the said vertical piece, said lever having its upper end bifurcated and having journaled in said bifurcated portion a suitable roller, the latter working in the irregular slot of the cam, an arm extending laterally from the front vertical piece, and a wire-carrying slide mounted upon said arm and connected to the lever pivoted to the side of the vertical piece, substantially as set forth.

11. In a button-setting machine, the combination of a standard formed or provided with an extension at right angles thereto, a

vertical piece secured to said standard, a bracket having its rear downwardly-flanged portion secured to the vertical piece and its forward upwardly-flanged portion bifurcated, a lever having its forward end formed into a yoke and pivoted to said bifurcated end of the bracket, said lever being also provided with an elongated slot to the rear of said yoke portion, a combined knife and crimper having an upwardly-extending bifurcated portion, the members or arms of said bifurcated portion being arranged upon opposite sides of the lever and provided with the apertures registering with the elongated slot of said lever, a cam provided with a laterally-extending arm passing through the apertures of the combined knife and crimper and through the elongated slot of the lever, an arm pivoted to the side of the vertical piece and having its upper end bifurcated, and a suitable roller journaled therein, said roller working in the irregular slot of the cam, an arm extending laterally from the vertical piece, and a wire-carrying slide mounted upon said arm and connected to the lever pivoted to the side of the vertical piece, substantially as set forth.

12. In a button-setting machine, the combination of a standard formed or provided with an extension at right angles thereto, a vertical piece secured to said standard, a combined knife and crimper, a front plate secured to said vertical piece and provided with an elongated slot, a chute connected to said front plate, a lever for operating said knife and crimper, a cam having a laterally-extending arm connected to the vertical lever, a lever pivoted to the side of the vertical piece, said lever having its upper end bifurcated and having journaled in said bifurcated portion a suitable roller, the latter working in the slot of the cam, an arm extending laterally from the front vertical piece, a wire-carrying slide mounted upon said arm and connected to the lever pivoted to the side of the vertical piece and provided with a forwardly-extending pin, and a spring-actuated bearing-plate pivoted to the front plate and having its outer end inclined and constructed to be engaged by the forwardly-extending pin of the slide, substantially as set forth.

13. In a button-setting machine, the combination, with a frame, of an automatically-operating lever mounted in the lower portion of said frame carrying on its forward end a clinching-die, an automatic vertically-moving combined crimper and knife, an automatic inwardly and outwardly moving staple-forming die, an automatic wire-carrying slide for feeding the wire to the eye of the button, a vertical bracket secured to the frame and carrying a revoluble reel consisting of a series of connected button-tubes conforming to the shape of the buttons, a front plate provided with an elongated slot, springs at the lower end of said slot, a transverse spring-actuated shaft at the upper end of the front

plate carrying a central and end crescent-shaped stop, the end stop constructed to be engaged by the forwardly-extending pin from the crimper and knife passing through a side slot in said front plate, and a chute, substantially as set forth.

In testimony that I claim the foregoing as

my own I have hereunto affixed my signature in presence of two witnesses.

WILLIAM M. GERKEY.
